RENÉ PAUL DÉSIRÉ FRÉRET AND PIERRE URBAIN MAURAN, OF PARIS, FRANCE.

SETTING-UP MACHINE.

1,279,098.

Specification of Letters Patent. Patented Sept. 17, 1918.

Application filed March 26, 1914. Serial No. 827,478.

To all whom it may concern:

Be it known that we, RENÉ PAUL DÉSIRÉ FRÉRET, of 71 Rue de Rennes, Paris, France, engineer, and PIERRE URBAIN MAURAN, of 68 Rue Marcadet, Paris, France, commercial agent, have invented new and useful Improvements in Setting-Up Machines, which improvements are fully set forth in the following specification.

10 This invention has for its object an arrangement for automatic line spacing to be applied to setting up machines whether movable type, monotype, rototype, or other.

15 In such machines each line of type is led in front of a vertical shutter having an up and down movement and placed at the inlet to the type galley, and is pushed into the galley by a pusher which has a to and fro movement and advances when the shutter 20 is raised.

According to this invention a space line galley is placed in front of the shutter above the space occupied by the type lines on arrival in front of the type galley, the 25 space line galley is provided adjacent to the shutter with a slot of adjustable size through which the space lines can move downward to come also in front of the type galley; the shutter is for this purpose provided with a shoulder upon its minor face.

30 At each descent of the shutter a fresh space line is placed in front of the type galley; then after a new line of type has been brought to the same spot and so soon as the 35 shutter is lifted the space line and the line of type will be pushed together into the type galley by the pusher.

The accompanying drawings illustrate two methods of carrying out the invention.

40 Figure 1 is a vertical section, Fig. 2 is a front elevation of the space line galley. Figs. 3 and 4 are a side elevation (partially cut away) and a plan of a modification. Fig. 5 is an elevation of the shutter, and 45 Fig. 6 shows details.

1 is the type galley, 2 the pusher having a to and fro movement which serves to push the lines of type and the space lines thereinto and 3 the upwardly and downwardly 50 moving shutter placed at the inlet to the galley 1.

The space lines *a* to be introduced are placed in a galley consisting of a box 4 open at the top, and at the side adjacent to the 55 shutter; its bottom is leveled near to this

side and stops at a certain distance from the face 3^a of the shutter; the bottom of the box rests partly on a plate 5 whose position can be regulated, for example, by means of a screw 6 in such a manner as to form 60 between its edge 5^a and the face 3^a of the shutter a slot of a size less than the thickness of a space line. In order to indicate the extent of rotation of the screw 6 and hence the extent to which the slot has been 65 enlarged or narrowed, a pointer 61 moving in front of the dial 62 is mounted on the shaft of the screws. The space lines are pushed against the shutter by means of a pusher 7 actuated, for example by springs, 70 and they are guided between one of the side partitions of the box and a movable partition 8, whose position is regulated according to the length of the space lines. This partition can be fixed, for example, 75 by means of a thumb screw 9, passing through grooves on plates 10 and 11 with which the galley 4 is provided. The shutter is provided with a shoulder 3^b whose thickness is less than that of the space lines 80 and which is adapted to move the space lines downward.

In order to resist the thrust of the space lines the shutter is strengthened by a rib 3^c.

At each rise of the shutter its shoulder 3^b 85 comes a little above the space lines so that one of these comes beneath the shoulder and moves as indicated in the drawing with the shutter when the latter moves downward. The space line is there maintained vertical 90 by the action of a blade spring 12 placed at the side of the arriving type lines and actuated by any suitable arrangements, for example, by means of abutments and frictional connections between the shutter, the 95 support of the spring and a driving member.

When one of the lines *b* comes in front of the lowered space line the spring 12 is raised a little above this so as to free it; 100 the shutter 3 then rises and the pusher 2 advances in such a manner as to push the space line and the line of type into the type galley 1. Then before the shutter 3 again moves downward bringing with it a 105 fresh space line the spring 12 is lowered in such a manner as again to assume its original position and to maintain the space line vertical so soon as this latter has moved downward.

The pusher 7 may actuate an alarm in such a manner as to announce the exhaustion of the space lines.

In place of the arrangement of screw and plate illustrated, the size of the space between 3^a and 5^a may be regulated by any other suitable arrangement, such as a cam for example.

In the modification illustrated in Figs. 3 to 6, 4 is the box forming the galley containing the space lines *a* to be introduced; the bottom 13 of the box comprises adjacent to the shutter 3 a movable portion 13' which can slide in suitable guides in the fixed portion of the bottom under suitable control, for example, a screw 14, bevel pinions 15, 16 and hand wheel 17. Upon the shaft 18 of the pinions 16 and of the hand wheel 17 is mounted a disk 19 provided with notches 20 in one of which a spring pawl 21 can engage. By suitably turning the hand wheel 17 in such a manner as to cause the spring pawl 21 to engage in one or other of the notches 20, the position of the movable bottom 13' can be regulated in such a manner as to produce between its rear edge 13' and the face 3^a of the shutter a slot of a thickness less than a space line (or of two or three space lines).

The space lines are guides as before in the box 4 between one of its side partitions and a movable partition 8, which may be rendered stationary by aid of a thumb screw 9 passing through grooves formed in the plates 10 fast with the galley 4. The pusher 7, which serves to push the space lines against the shutter 3, is actuated by flexible connections, such as belts, ropes or spring blades 22, fixed on the one hand to the pusher and passing over guide pulleys 23, then being wound up and having their other ends fixed to pulleys 24 mounted upon a common shaft 25 fast with the galley 4. Upon this shaft are also mounted ratchet wheels 26 with pawls 27 and spring barrels 28 which cause the advance of the pusher 7, and consequently that of the space lines.

In front of the galley 4 is placed a special arrangement which allows of locking and arresting the space lines and the pusher 7 when it is desired to remove the galley 4 from the rest of the apparatus, the galley being for this purpose detachably mounted.

This arrangement comprises a cam 29 mounted upon a shaft 30 fast with a lever 31 having a spring pusher 32. This latter engages in notches 33 on a fixed support 34. The lever may occupy the two positions 31 and 31'.

In the first position the cam 29 allows a lever 35 pivoted at 35' to rise under the action of its spring 36. A finger 37 fast with the other end of the lever 35 is then lowered and arrests the space lines at the end of the galley 4. If on the contrary the

control lever comes into the position 31' the cam 29 lowers the lever 35 and raises the finger 37, thus liberating the space lines.

In this modification the spring 12 is replaced by a secondary support 38 parallel to the shutter 3 and fixed at both ends to a slide 39 having a spring 40, such slides acting at the ends of the shutter 3 and allowing it to permit the passage of the line when the shutter rises. At this moment the slides 75 are acted upon by their springs 40 which causes the shutter 38 to rise allowing the passage of a type line and a space line below it, these lines being pushed into the galley 1 by the pusher 2. An abutment 41 fixed 80 for example to a plate 42 by a rod 41' passing through a groove 43 formed in the shutter 3 and actuated by a worm 44 regulated by a milled head 45, serves to maintain 85 the space lines in front of the inlet of the galley 1.

Having now particularly described and ascertained the nature of our said invention and in what manner the same is to be performed, we declare that what we claim is:— 90

1. In a setting-up machine, a space line galley and a shutter adapted to reciprocate in front of the same, in combination with a main composition galley arranged substantially parallel to the space line galley, 95 and a pusher adapted to intermittently push forward the combined space and type lines as they are assembled in the main galley, the shutter being adapted to push a space line from its galley to the entrance of the 100 main galley.

2. In a setting-up machine, a space line galley and a shutter adapted to reciprocate transversely in front of the same, in combination with a main composition galley arranged substantially parallel to the space line galley, and a pusher adapted to intermittently advance the combined space and type lines as they are assembled in the main galley, the space line galley being provided with a longitudinally adjustable bottom for regulating the space between the front edge of the bottom of said space line galley and the shutter, said shutter being adapted to push a space line from its galley to the 110 entrance of the main galley. 115

3. In a setting-up machine, a space line galley, a main composition galley substantially parallel thereto, and a shutter adapted to reciprocate in front of the space line galley to push a space line from the space line galley to the entrance of the main galley, in combination with a member having an upward and downward movement distinct from that of the shutter and serving to 120 maintain the space lines in a vertical position as they are fed to the main galley, and a pusher adapted to advance the assembled space and type lines in the main galley. 125

4. In a setting-up machine, a space line 130

galley and a yielding pusher to advance the space lines to the front of the galley, in combination with a pivoted lever at the front of the galley carrying a stop arranged to arrest the advance of the space lines at the front of the galley, means for yieldingly urging the stop into an operative position to arrest the type, and a cam lever arranged to force the lever out of its operative position in opposition to the yielding means.

5. In a setting-up machine, a space line galley and a pusher for yieldingly advancing the space lines in the galley, in combination with a flexible connection secured di-

rectly to the pusher, a guide pulley to guide 15 the flexible connection, and a spring barrel provided with a pawl and ratchet retaining device, the flexible connection being secured to said spring barrel.

In testimony whereof we have signed this 20 specification in the presence of two subscribing witnesses.
